UNITED STATES PATENT OFFICE.

SAMUEL M. FORD, OF DES MOINES, IOWA.

HEATING-STOVE.

1,165,165.

Specification of Letters Patent. Patented Dec. 21, 1915.

Application filed August 11, 1915. Serial No. 44,888.

To all whom it may concern:

Be it known that I, SAMUEL M. FORD, a citizen of the United States, and a resident of Des Moines, in the county of Polk and State of Iowa, have invented a new and Improved Heating-Stove, of which the following is a full, clear, and exact description.

This invention relates to stoves and furnaces and has particular reference to heaters employing liquid fuel.

Among the objects of the invention is to provide a heating apparatus adapted especially for the use of kerosene as a fuel and comprising a drum within or below which are adapted to be arranged one or more burners to which the oil is fed from a tank supported outside of the drum.

A further object of the invention is to provide an improved shield or protector between the drum and the tank insuring the utmost safety in the use of the device.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a perspective view indicating a preferred embodiment of the invention wherein three separate burners are employed within a cylindrical drum; Fig. 2 is a plan view, parts being in section on the line 3—3 of Fig. 2; and Fig. 3 is a vertical sectional view on the line 3—3 of Fig. 2.

As illustrated, the invention comprises a pan-like base 10 having supporting legs 11 secured to the upwardly projecting flange or rim 12 thereof. The periphery of the base is reinforced and stiffened by means of a band 13 extending around within the flange 12 and held in place by the bolts 14 which secure the legs in place.

Above the base and spaced from the reinforcing band 13 is a hollow drum 15 having open upper and lower ends. This drum is secured in place preferably by means of standards 16 indicated herein as four in number corresponding to the legs from which they project upwardly. The drum is secured to the standards by means of bolts or other similar fasteners 17. The upper

ends of the standards are bent inwardly at 18 in a plane above the open end of the drum and constitute supports for a top 19, the main portion of which is substantially flat but bounded by an outwardly and downwardly projecting flange 20 spaced above and outwardly from the upper edge of the drum.

At 21 I show a reservoir or tank for liquid fuel supported in any suitable manner outside of the drum as upon a pipe 22 through which the fuel is conveyed downwardly and inwardly to or about the center of the pan-shaped base. 23 is a diagrammatic representation of a plurality of burners communicating with the elbow portions 24 of the fuel pipe. Said burners being of conventional form and not constituting any part of the invention *per se* are not specifically illustrated. Suffice it to say, however, that the burners are accessible through the open space between the drum 15 and the base of the stove for the purpose of controlling the burning thereof. The condition of the flame at the tops of the burners may be observed through a peep sight or window 25 arranged in the front of the drum at about the level of the tops of the burners. The heat generated at the burners fills the top of the apparatus within the drum and below the top 19, thereby thoroughly heating these parts and from the outer surfaces of which the heat is radiated most effectively. A portion of the heat is deflected downwardly on the outside of the drum by virtue of the flange 20. As indicated best in Fig. 2, a majority of the burners are located on that side of the drum from the tank, thereby insuring that the center of gravity of the apparatus will remain well within the space determined by the legs 11.

The guard means above referred to comprises a main shield 26 of a length vertically substantially equal to the distance between the base 10 and the flange 20 of the top and spaced outwardly from the drum between the drum and the tank 21. This shield 26 comprises preferably a section of a hollow cylinder formed concentrically with the drum and providing an air space therefore between it and the drum, as shown at 27. As a convenient means to secure the shield 26 in place, I provide an auxiliary shield 28 spanning the space between the base and the lower portion of the drum and protecting the main shield 26 from the direct heat from

the rearmost burner 23. The main and auxiliary shields are connected by brackets 29 at the sides, and they are connected to each other and to the lower edge of the drum by 5 means of a bolt 30 surrounded by a spacing sleeve 31 between the two shields to prevent the tightening of the bolt from collapsing the shield structure.

The lower end of the shield is notched 10 out as shown at 32, to accommodate the fuel pipe 22, said pipe also lying in a notch 33 in the base flanges; hence the shield structure by means of the coöperation with the pipe is prevented from lateral displacement 15 at its lower end or in a direction circumferential of the stove. The lower end of the shield is held from radial displacement by means of lips 34 extending downwardly between the flanges 12 and 13 on opposite sides 20 of the pipe 22 and the upper end of the shield 26 is held from outward radial movement by means of a bracket 35 extending into a notch 36 at the top of the drum and extending downwardly inside the drum a 25 short distance. The bracket 35 also prevents circumferential movement of the shield by engaging the sides of the notch 36. The lower end of the drum 15 may be slotted, as indicated at 30', to facilitate the 30 assemblage of the guard means with the drum. The guard means described insures that the supply of oil in the tank will not be dangerously heated from the stove, and also the heat generated in the stove will not be 35 wasted. This kind of stove is of comparatively cheap construction, is easy and safe in operation and regulation, and has proved in practice to be most economical with respect to fuel consumption.

40 I claim:—

1. The herein described liquid fuel burning stove comprising a pan-shaped base, means to support the base in horizontal position, burner means within and above the 45 base, a vertical hollow heating drum supported in spaced relation above the base, a

flat top supported above the drum and having an outwardly and downwardly projecting flange, a fuel tank above the base and outside of the drum, and guard means located between the drum and the tank and spaced from both of them, said guard means also bridging the space between the base and the drum adjacent the tank. 50

2. In a fuel burning heating stove, the 55 combination of a base, means to support the base in a horizontal position, burner means within and above the base, a hollow drum above and spaced from the base and surrounding the upper end of the burner 60 means, a fuel tank at one side of the drum, a pipe leading therefrom over the base to the burner means, and guard means between the tank and the drum, said guard means comprising a shield extending from the base 65 to the top of the drum, the lower end of the shield being notched for coöperation with the means to convey the fuel from the tank, and means to secure the guard means to the base and the drum holding the same from 70 movement in any direction.

3. In a liquid fuel heating stove, the combination of a base, a drum above and spaced from the base, burner means within the space between the base and the drum, a fuel 75 tank outside of the drum, and guard means between the drum and the tank, said guard means comprising a main shield extending upwardly from the base between the tank and the drum, an auxiliary shield between the 80 base and the lower edge of the drum, means securing the main and auxiliary shields in definite spaced relation to each other, and means extending downwardly from the auxiliary shield into coöperation with the base 85 to prevent displacement of the guard means, substantially as set forth.

SAMUEL M. FORD.
